United States Patent Office.

JOHN H. BELLAMY, OF CHARLESTOWN, MASSACHUSETTS, ASSIGNOR TO SAMUEL D. NILES AND BENJAMIN A. WARD.

Design No. 4,466, dated November 15, 1870.

DESIGN FOR A BRACKET.

The Schedule referred to in these Letters Patent and making part of the same.

To all whom it may concern:

Be it known that I, JOHN H. BELLAMY, of Charlestown, county of Middlesex and State of Massachusetts, have originated and designed a new and useful Pattern for a Bracket, of which the following is a full and exact description, reference being had to the accompanying photographs.

The design for a bracket herein set forth is:

Above the shelf A is a circular ray, B, inclosing a cross, D, and crown C, above which is a square, E, compass G, inclosing a double cross, F, above which is an arch, I, and cross H.

On the right of the ray is a cross, J, and on the left

of the ray is a nine-pointed star, K, on which is a cross, L, and a serpent, M.

Below the shelf A, and on the right of the shelf-support, are cross-swords N N, and on the left a tent, O, the shelf being supported by a square, P, and bugle R, all in ornamental scroll-work.

What I claim as my invention, and desire to secure by Letters Patent, is—

The design or pattern for bracket herein set forth.

JOHN H. BELLAMY.
